UNITED STATES PATENT OFFICE.

FRANK L. O. WADSWORTH, OF SEWICKLEY, PENNSYLVANIA.

WATER-HEATER CONSTRUCTION.

1,120,571.

Specification of Letters Patent.

Patented Dec. 8, 1914.

Application filed January 25, 1913. Serial No. 744,198.

To all whom it may concern:

Be it known that I, FRANK L. O. WADSWORTH, a citizen of the United States, residing at Sewickley, in the county of Allegheny and State of Pennsylvania, have invented certain new and useful Improvements in Water-Heater Construction, of which the following is a specification.

My invention relates to the automatic control mechanism for regulating the supply of fuel to the burner system of water heaters, particularly heaters of the so-called instantaneous type in which gas is burned only when water is flowing through the heater coils. One of the principal objects of my invention is to produce a mechanism by which the movements of the single main fuel valve are synchronously, but indirectly controlled, (first) by the movements of a water-actuated element in such manner that said fuel valve is caused to open when a flow of water is started through the heater and caused to close when said flow is stopped, and (second) by the movements of a thermostat member in such manner that the fuel valve is caused to close when the temperature of the flowing water rises above a certain point and caused to open when the temperature of the water flowing out of the heater falls below a certain point. This general result has been secured by various previously described forms of mechanisms; such for example as those shown in my co-pending applications Ser. Nos. 727,510 and 659,546, filed on October 24, 1912 and November 10, 1911 respectively. But in general such mechanisms are designed to act directly on the main gas valve; that is to say, are designed to produce by the direct movements of the water-actuated member and the thermostat member a corresponding direct movement of the main fuel valve. In my present invention, as above indicated, there is no such direct connection between the operating parts. Instead of this, I use the movements both of the water-actuated member and the thermostatically actuated member to simply control the application of a force which is independent of either of these power-actuated elements; this force being produced by or derived from the pressure of the gas in the main fuel supply pipe, or the pressure of the water in the heater (either the static pressure or the dynamic flow pressure) or a source of electro-magnetic energy, or some other suitable power developing means.

This method of indirect control of the movements of the fuel valve enables me to make the water-actuated mechanism and thermostatically actuated mechanism of very much lighter, simpler, and less expensive construction than is necessary when said mechanisms are required to act directly on the gas valves, and it also enables me to move said valve much more rapidly and positively than can be done by directly connecting it with a relatively slow moving and sluggishly acting thermostat member. Other advantages of my improved construction as applied to a heating apparatus of the character above mentioned will be readily apparent to those skilled in the art from the following descriptions of various embodiments of my present invention.

In the drawings which form a part of this specification, Figs. 1 and 2 illustrate in front and side elevation respectively the general construction of a hot water heater of the so-called instantaneous type; Fig. 3 is an enlarged cross-sectional view through the center of the control mechanism used in the construction of Figs. 1 and 2; Fig. 4 illustrates a modified construction and arrangement of some of the parts shown in Figs. 1, 2 and 3; Fig. 5 is a similar cross-sectional view through the center of another control mechanism embodying my improvements; Figs. 6, 7 and 8 are sectional illustrations of other embodiments of my invention.

Referring first to the general arrangement of the heater parts as shown in Figs. 1 and 2; A is the casing of the heater; B indicates the upper coils of the heater; C is the lower reverse coil connected to the upper coils by means of the pipe D; E are the gas burners mounted upon the usual burner ring; F is the gas supply pipe; G is the casing of the gas valve for controlling the supply of gas to the burners; H is the gas pipe leading from the gas valve to the ring which carries the burners E; I is the casing of the thermostat; and K is the casing of the water actuated member for securing the operation of the gas valve when the outlet from the heater is opened and closed.

Referring now to Fig. 3 in conjunction with Figs. 1 and 2; 1 indicates the pipe through which cold water passes from the main to the chamber 2 containing the water-actuated member of the control mechanism; 3 indicates the water inlet to the top heater

coil A; 4 indicates the outlet from the bottom reverse coil C of the heating receptacle, this latter outlet communicating through ports 5, 5, etc., with the lower end of the vertical thermostat chamber 6; and 7 indicates the pipe leading from the upper end of said thermostat chamber to the house supply system. The gas, or suitable fuel, which supplies the main heating burners F is led into the control apparatus through a pipe F to the main gas valve casing G in which is located the valve 8 which controls the flow of fuel through the pipe I leading to the heating burners E. This valve 8 is mounted on and supported by a thin flexible diaphragm 9, made of leather, parchment, metal foil, or other suitable material, which in this case, is of considerably larger diameter than the valve 8 and is clamped in position between the open side of the main gas valve casing G and a shallow recessed cap 10. This cap 10 is provided on its central vertical diameter with a tubular enlargement or cavity 11 having port openings 12 and 13 at the top and bottom which afford communication between the shallow space ~~back~~—i. e., to the right—of the diaphragm member 9 and passage-ways 14 and 15 that lead respectively to the interior of the gas inlet pipe F and to the gas outlet pipe H. The ports 12 and 13 are opened and closed by means of two valves 16 and 17 mounted on a common stem 18 which passes up through a stuffing box above the port 12 and terminates opposite an adjustable screw 19 in the end of the lever 20 whose movement is controlled by the thermostat. The stem 18 and valves 16 and 17 are normally held in the position shown in the figure—in which the port 13 is closed and the port 12 is opened—by means of a spring 21. The thermostat by means of which the lever 20 is operated is of the general construction more fully illustrated and described in my co-pending application Serial No. 699,816. The positive expansion member of this thermostat consists of a wire 22 of hard drawn copper, brass, phosphor bronze or similar suitable metal, which is secured at one end at the point 23, is led successively around the steps of lower and upper coned pulley elements 24 and 25, is then led out through a stuffing box 26 in the lower head of the thermostat chamber 6, and secured to a collar 27. A knife edge 28 bearing on the lower side of the lever 20 is threaded on the wire just above the collar 27 and a short compression spring 29 is interposed between the knife edge and said collar to provide for a small relative movement of one with respect to the other. A tension spring 29 secured to the thermostat lever 20 serves to keep the wire 22 under practically constant tension as it expands and contracts with changes of tem-

perature. The upper and lower coned pulley elements 24 and 25 are mounted on knife edges at the two ends of a spacing bar 30 which is of nickel steel, invar metal, or similar material having a co-efficient of expansion very much less than that of the wire 22, this spacing bar 30 being suitably supported in position on a post 31 bolted to the lower head of the thermostat chamber 6. It is apparent that the expansion and contraction movements of the successive strand sections of the wire 22 which pass between the upper and lower pulley elements are cumulative in effect and the diameters of the successive steps of the pulley elements 24 and 25 are in the ratio of the odd numbers, 1, 3, 5, etc., for the lower element, and are in the ratio of the even numbers, 2, 4, 6, etc., for the upper element, so that there is no slip between the various parts of the wire 22 which lie on these steps and the steps themselves. Hence the movement of the collar 27 at the lower end of the wire 22 under a given change in temperature is the same as that of a straight wire secured at its other end to a point on a nickel steel or invar metal pipe leading up from the lower end of the chamber 6, and of a length equal to the sum of the lengths of all the successive strand sections. The construction above described enables me to use in the relative short thermostat chamber 6 such a total effective length of wire as will eliminate the necessity of employing any large multiplication of the thermostat lever system in order to secure the necessary movement of the screw 19 which acts upon the stem of the valves 16 and 17; and therefore enables me to produce the very simple and compact arrangement of parts shown in Fig. 3.

The outer end of the passage-way 14 which leads into the gas supply pipe H is opened and closed by a valve 32 which is secured to the lower end of a stem 33 that passes upward through the vertical section of the pipe H, through a stuffing box at the top of that section, and through an adjacent stuffing box in the lower head of the chamber 2. At the upper end of this stem, in the chamber 2, there is secured a puppet valve 34 which constitutes the water actuated member of the control mechanism. Just above this valve 34 is a second smaller valve 35 which is adapted to open and close the port opening 36 leading from the chamber 2 to the upper end of the thermostat chamber 6.

The operation of this mechanism is as follows: When no water is flowing through the heater, the valve 32 is held against its seat by the weight of the stem 33 and valve head 34—supplemented if desired by a compression spring such as that shown at 37—and the closure of this valve prevents any

gas from entering the chamber 11 at the right hand side of the diaphragm 9, even though the port 12 may be open. Under such circumstances the diaphragm 9 is exposed to the gas pressure only on the left hand side, and this pressure holds the main gas valve 8 against its seat thus preventing any fuel passing through it to the main heating burners. But as soon as the flow of 10 water through the heater is started—as by opening a tap in the house supply system—the pressure on the upper side of the puppet valve 34 is reduced by the outflow of water, and this puppet valve will be raised, opening 15 the valve 32 and closing the valve 35. The opening of the former valve allows the gas to flow into the chamber 11—if the port 12 is open at that time, as it will be if the temperature of the water in the thermostat 20 stat chamber is below the predetermined point of cut-off—and this inflow of gas to the chamber 11 equalizes the pressure on the two sides of the diaphragm member 9, thus allowing the gas valve 8 to be opened 25 by the unbalanced pressure of the gas on its right hand side. As the temperature of the water in the thermostat chamber rises the wire 22 will expand allowing the lever 20 to be pulled down by the tension of the 30 spring 29 until the screw 19 engages with the end of the valve stem 18 thus closing the port 13. When this occurs the gas back of the diaphragm;—i. e., on the right hand side,—flows out through the passage way 35 15 and the ejector orifice at the end of that passage-way into the gas outlet pipe I. This once more relieves the pressure on the right hand side of the diaphragm 9, and the unbalanced pressure of the gas on the 40 left hand side closes the valve 8 and cuts off a further flow of fuel to the main burners of the heater. Any slight expansion of the thermostat wire 22 which takes place after the seating of the valve 16 is taken 45 care of by the expansion of the spring between the collar 27 and the knife edge 28, so that the wire 22 is maintained constantly under tension. When the temperature of the flowing water falls again the wire 22 50 will contract lifting the lever 20 against the tension of the spring 29 and freeing the stem 18 from engagement with the screw 19. The valve stem 18 and the valves 16 and 17 will then be raised by the tension 55 of the spring 21 thus closing the port 13 and opening the port 12. This reestablishes equal gas pressures on the two sides of the diaphragm member 9 and permits the main gas valve 8 to be opened as previously described. As long as water continues to flow 60 through the heater—thus keeping the valve 32 opened—the above described opening and closing movements of the main gas valve 8 will be effected by the balancing and unbal- 65 ancing of the gas pressure on the two sides of the diaphragm member 9 whenever the temperature of the water in the thermostat chamber falls below or rises above the predetermined point of cut-off for which the thermostat may be set to act by adjustment 70 of the screw 19. When water ceases to flow, however, the valve 34 will fall, thus closing the valve 32 and preventing any further passage of the gas from the inlet pipe H to the chamber 11. If, at this time, the chamber 11 is filled with gas, the gas valve, of course, remains open until the water in the apparatus has been heated up to the point of cut-off and the port 13 is opened. The gas remaining in the chamber 11 will then 75 flow out and the main gas valve 8 will be permanently closed until a fresh actuating supply of gas has been admitted to the chamber 11 by the opening of the water controlled valve 32.

When the valve 34 is closed, the valve 35 is always open thus allowing the water to circulate freely through the thermostat chamber 6 between the inlet and outlet openings 3 and 4 of the heater coils. 80

In Fig. 4 I have illustrated in vertical cross-section another form of my improved control mechanism. In this construction water flows from the main through the pipe 1' to the chamber 2' and thence directly into the inlet 3' communicating with the top coil A of the heating receptacle. After flowing through the successive coils A to C, the water emerges from the outlet 4', enters the lower end of the thermostat chamber 6', and 95 after flowing upwardly through said chamber, enters the pipe 7' leading to the desired point of discharge. At the upper end of the thermostat chamber 1 provide a port 36' which leads into the chamber 2'. This port 100 is opened and closed by a valve 40 held in position by wings engaging with the sides of the port 36' and by a stem, the end of which enters a recess 41 in the wall of the thermostat chamber. When no water is 105 flowing through the apparatus, this valve is held open by means of a weak spring 42, thus allowing the water to circulate freely through the thermostat chamber 6' and the port 36' between the inlet 3' and the outlet 110 4' of the heater coils. The fuel supply enters the main gas valve casing G' through a pipe F' and passes out—when the main gas valve 8' is opened—through the pipe 7' which leads to the main burners of the 115 heater. A cut-off valve 42 is inserted in the inlet pipe F' as usual, and the inlet side of this valve is provided with a connection from which the pipe 43 passes to the usual pilot light. The main gas valve 8' is in this 120 construction supported on a stem 44 which passes through a stuffing box in the right hand wall of the gas valve casing G' and is attached at its outer end to the center of the thin flexible diaphragm member 45. The 125 130

gas valve 8' is not secured directly to the stem 44 but is held in position against the inner head thereof by means of a leaf spring 46 which permits the stem 44 to move 5 slightly with relation to the gas valve, the latter being normally closed against its seat by the compression spring 47. A passage-way 14' leads from the inlet side of the main gas valve casing chamber to the space or 10 chamber 48 between the right hand head of said chamber and diaphragm member 45; and a second passage-way 15' leads from said space to an ejector outlet 38' that enters the gas outlet pipe H'. The openings from 15 the passage-ways 14' and 15' to the chamber 48 are controlled by valves 16' and 17', which are mounted on a valve stem 18' (forked at its center to pass around the stem 44) and are normally held in the position shown in 20 the figure, in which the valve 16' is open and the valve 17' is closed, by a compression spring 21'. The outer end of the passage-way 14' is also closed by another valve 32' mounted on a stem 31' which passes up 25 through a stuffing box in the top cap of the gas valve casing G', then through a second stuffing box in the lower end of the cylinder 49 and is secured to the water-actuated piston member 50 in said cylinder. The lower 30 end of the cylinder 49 is connected to the chamber 2' by means of a pipe 51, and the upper end of said cylinder is connected to the thermostat chamber 6' by a port or passage way 52. The piston member 50 is normally held in its lowest position, in which the valve 32' is closed by means of a compression spring 53. The actuating thermostat member which I use in this case to control the movements of the valves 16' and 17', 35 is of the usual composite construction, save that the outer expansion tube 54 and the inner negative element 55 may both be made very light because the thermostat member does not have to move the auxiliary controlled valves just mentioned. The lower 40 knife edge terminal of the inner negative element 55 bears against the short arm of a bell crank lever 56, and the long arm of said lever is provided with an adjustable screw 57 which bears in turn upon the short 45 arm of a second bell crank lever 58. The longer arm of the lever 58 is also provided with an adjustable screw 60 which engages with the lower end of the stem 16'. A 50 spring 59 attached to the lower end of the lever 56 serves to keep said lever in operative engagement with the negative thermostat element 55. 55 The operation of this mechanism is in 60 general similar to that already described. When no water is flowing through the ports, the piston 50 will be held down by the spring 53 and the valve 32' will be closed, preventing any gas from flowing into the 65 chamber 48. But as soon as a flow of water is started through the apparatus by opening some outlet in the pipe 7' the pressure on the upper side of the piston 50 is diminished and the superior pressure of the inflowing water on the lower side thereof will raise 70 the piston and open the valve 32'. If the valve 16' is open—as it will be if the temperature of the flowing water is less than that of the predetermined cut-off point—the gas will flow on through the passage-way 75 14' to the chamber 48 and exert a pressure on the inside of the diaphragm 45 sufficient to overcome the tension of the spring 47 and thus open the main gas valve 8' allowing fuel to flow past said valve through the outlet pipe I to the main burners of the heater. As the temperature of the flowing water rises, the thermostat member 54 will expand, lifting the negative member 55 and allowing the spring 59 to move the thermostat lever 56—and with it the lever 58—until the screw 60 has been brought into engagement with the lower end of the stem 18'. The further movement of the thermostat parts 80 in the same direction will lift the valve 17' 90 from its seat—the tension of the spring 59 being sufficient to overcome the tension of the spring 21'—and simultaneously close the valve 16'. This will allow the gas in the chamber 48 to escape through the ejector orifice 38' and relieve the pressure on the inside of the diaphragm 45. The gas valve 8' will then be closed by the spring 47 thereby shutting off further flow of fuel to the main burners. The main gas valve 8' will 95 remain closed until the fall in temperature of the flowing water has caused the parts to once more assume the position shown in the figure in which the valve 16' is open and the valve 17' is closed. In this position—the valve 32' being still open—a fresh supply of gas is admitted to the chamber 48 and the pressure on the inside of the diaphragm 45 re-established, thereby again opening the main gas valve 8'. These movements of the main gas valve will continue as long as the water continues to flow through the apparatus and successively rises above and falls below the point for which the thermostatic mechanism may be set to cut off the gas; this point being varied at will by the adjustment of either the screw 57 or the screw 60. But as soon as the flow of water is stopped, the pressure on the two sides of the piston 50 are equalized and said piston is returned to 100 its lowest position thereby closing the valve 32' and preventing any further access of gas to the chamber 48. Any leakage of gas through the stuffing box around the stem 44 is prevented, when the gas valve is closed, by a leather washer 61 which is kept tightly pressed against the head of the valve stem stuffing box by means of a spring 46 and thus seals the opening around this stem 105 against any escape of gas even though the 110 115 120 125 130

stuffing box itself may be quite loose. If the main gas valve is open when the water is shut off, and the valve 32' is closed, it will remain open until the temperature of the water in the thermostat chamber has been raised to the point of cut-off, and the valve 17' opened. The gas valve will then close and remain closed until water has once more started to flow through the heater and has opened the valve 32', admitting gas once more to the chamber 48.

In Fig. 5 I illustrate still another embodiment of my invention, which differs from those previously described in the detail form of the water-actuated member and the thermostat member. In the construction of Fig. 5, water is brought to the apparatus through a pipe 1², the upper part of which is led directly to the cold water inlet (not shown in this figure) of the upper coil B of the heating receptacle. This pipe 1² is provided with a special elbow connection having a port opening 62 which registers with a corresponding port 63 that enters the right hand end of the chamber 64. This chamber contains the water-actuated element 65, which in this case is made in the form of a thin corrugated flexible diaphragm of hard rolled brass or copper sheeting or some similar suitable material. A stem 33², secured to the center of this diaphragm member, is led through suitable stuffing boxes in the head of the chamber 64 and the adjacent head of the main gas valve casing G² and terminates in a disk valve 32² that controls the port opening from the inlet side of the gas valve chamber G² to the passage way 14². The diaphragm member 65 is normally kept in the position shown in the figure, in which the valve 32², is seated by a compression spring 53². The passage-way 14² leads to a small chamber 66 that contains the auxiliary controlling valve 67. This valve 67 is double faced, and when down it closes the port opening 13² which communicates with the pipe 15² leading to the ejector orifice 38² that opens into the gas outlet pipe H² leading from the gas valve chamber G² to the main burners of the heater. When the valve 67 is down, as shown in the figure, it opens the port connection 12² which leads from the chamber 66 to the shallow space back—i. e., on top of—the flexible diaphragm member 9² to the center of which the main gas valve 8² is attached. The main gas valve 8² is in this case arranged in a horizontal position, and opens downwardly. A weak conical spring 68 is arranged below this valve and so adjusted in tension as to not quite support its weight. The water after passing through the heating coils emerges from the lower end thereof through the outlet 4², enters the thermostat chamber 6² (which in this case, is formed as part of the gas valve casing G²) and emerges from the opposite end thereof

through an elbow connection and pipe 7² leading to the house supply system or other desired point of discharge. A branch connection 69 leads from the outlet passage 4² to a port 52² entering the left hand end of the chamber 64. The thermostat member which I use in this case consists of two concentric corrugated metal tubes 70 and 71 which are hermetically closed at each end and the inclosed space thus formed is filled with some suitable liquid having a high coefficient of expansion—preferably also of considerable viscosity such as petroleum or olive oil—or filled with paraffin or some eutectic alloy that melts at a temperature less than that for which the thermostat may be desired to act. Both heads of this thermostat member are perforated at the center so as to allow the hot water to pass through the central opening of the inner tube 70 as well as around the exterior of the outer tube 71. The right hand head is secured in position to the cap 72 that closes the corresponding end of the thermostat chamber 6². The left hand head engages with the end of the stem 73 that passes out through a stuffing box in the adjacent end of the thermostat chamber 6² and bears against the thermostat lever 56². The outer end of this thermostat lever carries a double knife edge link connection 74 which engages with the short arm of a second thermostat lever 58². The long arm of this second lever is weighted to hold the lever parts in operative engagement with the stem 73, and is provided with an adjustable screw 60² that bears against the upper end of the stem 18² of the auxiliary controlled valve 67. The weight on the end of the lever 58² normally keeps the valve 67 pressed downward against its lower seat of the port 13². A weak compression spring 75 is interposed between a collar on the stem 18² and the head of the stuffing box through which said stem passes, and acts to lift the valve 67 against its upper seat—thus closing the port opening between the chamber 66 and the passage 12²—when the screw 60² is lifted out of engagement with the upper end of the stem. The operation of the control mechanism of Fig. 5 differs in no essential respect from that of the previously described mechanisms, and will therefore be readily understood with a very brief description. When no water is flowing through the apparatus, the valve 32² is held closed, thereby preventing any gas from entering the passage way 14². Under these circumstances the lower side only of the diaphragm 9² is exposed to gas pressure, and the area of the diaphragm 9² being considerably larger than the area of the main gas valve 8², the latter is closed against its seat preventing all flow of fuel to the gas outlet pipe H². As soon as the flow of water is started, a

differential pressure is established on the two sides of the diaphragm member 65 by the resistance to the flow of water through been raised to the point of cut-off, and the 5 will cause the diaphragm 65 to move to the left against the tension of the spring 53², thus opening the valve 32² and allowing gas to flow into the passage-way 14². If the temperature of the flowing water is less 10 than that for which the thermostat is set to cut off the gas supply, the gas supply valve 67 will be seated in its lowest position, as shown in the figure, and the gas that flows in through the passage 14² will enter 15 the space above the diaphragm 9², and the main gas valve 8² will be opened, partly by the action of gravity, and partly by the unbalanced pressure of the gas on its upper side, thus allowing fuel to flow to the pipe 20 H² and thence to the main burners of the heater where it will be ignited by the usual pilot light provided for that purpose. As the temperature of the flowing water is raised by the heating effect of the main 25 burners the thermostat member will expand moving the stem 73 to the left and lifting the screw 60² out of engagement with the stem 18². This will allow the spring 75 to lift the valve 67 thereby closing the port 30 above the valve and opening the port 13² below the valve. The gas above the dia- 35 phragm 9² will then flow out through the pipe 15² and the ejector orifice 38² and the main gas valve 8² will be lifted by the unbalanced pressure of the gas against the lower side of the diaphragm 9². The gas valve will remain closed until the cooling down of the flowing water contracts the thermostat member sufficiently to allow the 40 screw 60² at the weighted end of the thermostat lever 58² once more to engage the stem 18² and force down the valve 67 to the first described position. The main gas valve 8² will then again be opened as before 45 described. These opening and closing movements will, of course, continue as the temperature of the flowing water successively falls below and rises above the point of predetermined cut-off—which is determined 50 by the adjustment of the screw 60². But when water ceases to flow through the apparatus the pressures on the two sides of the diaphragm 65 will once more be equalized and said diaphragm member will be 55 returned to its initial position by the action of the spring 53² thus closing the valve 32² and preventing any further access of gas to the back of the diaphragm member 9². If this cut-off by the water-actuated member occurs at the time when the temperature 60 of the flowing water is below the point of thermostatic cut-off, the main gas valve 8² will remain open until the water in the heater—and the thermostatic chamber 65 which in this case is in immediate communica-

cation therewith—has reached the point at which the valve 67 is raised. The gas confined above the diaphragm 9² is then discharged and the gas valve 8² remains permanently closed until the reestablishment of 70 the water flow through the heater admits a fresh supply of gas to the passageway 14².

In Fig. 6 I illustrate the construction of a control mechanism in which the main gas valve is actuated in its movement by the 75 pressure of the water in the apparatus acting on a diaphragm to which the main gas valve is secured. The admission and withdrawal of water to and from the space back of this diaphragm is jointly controlled, as 80 in previous mechanisms, by a set of valves, one of which is opened and closed by the starting and stopping of the flow of water through the heater, the others being opened and closed by the variations in temperature 85 of the flowing water through the medium of proper thermostatically-actuated mechanism. In the figure, 1¹ indicates the pipe leading from the water main to the chamber 2⁸ containing the water-actuated control member 34⁸. This water-actuated member is a puppet valve similar in form to that shown in Fig. 3 with an upper head 35⁸ which is adapted to open and close a port 36⁸ leading to the upper end of the 90 thermostat chamber 6⁸. A stem 33⁸ is loosely secured to the lower side of the valve 34⁸ and extends downward to a valve 32⁸ which is adapted to open and close a port leading from the chamber 2⁸ to a water 95 pipe 76 that passes downward to a chamber 77. In the lower part of this chamber there is a valve 16⁸ which opens and closes the outer end of a passage-way 78 leading to the back—i. e., to the left hand side—of 100 a diaphragm 9⁸, which in this case is of relatively small diameter, and is made of heavy rubber faced with canvas or leather, or is made of thin corrugated metal, so as to be capable of safely withstanding the 105 maximum pressure to which the water in the apparatus is subjected. The main gas valve 8⁸ is riveted or otherwise suitably secured to the center of this diaphragm member, and is commonly held closed by means 110 of a strong compression spring 79. A second valve 17⁸, located near the diaphragm end of the passage-way 78 opens and closes a port leading from this passage-way to a pipe 60 which is preferably led downward 115 through the shell of the heater to the usual drip pan located below the main heating burners F. Both the valves 16⁸ and 17⁸ are mounted on stems which pass upwardly 120 through stuffing boxes in the top wall of the passage-way 78 and terminate opposite two adjustable screws 81 and 82 in the ends 125 of a two-armed thermostat lever 83. Mounted in the thermostat chamber 6⁸ is the actuating thermostat member which in this case 130

is made up of a circular nest of iron or nickel steel tubes 84, 85, 86, etc., closed at the top and opening at the bottom into a cap 87, to the lower end of which is secured 5 a flexible metal diaphragm box 88; the closed interior of the tubes, cap and box being filled with a suitable positive expansion medium such as some relatively dense liquid or a solid melting at a temperature less 10 than that for which the thermostat may be desired to act. The lower head of the box 88 is recessed to receive the upper end of a bar 89, the lower end of which engages with the central upper knife edge slot of the 15 thermostat lever 83. This upper knife edge slot is off-set slightly with reference to the lower and supporting knife edge slot of said thermostat lever so that the thrust of the bar 89 acts on a short lever arm which 20 is inclined at an angle of 75 to 80 degrees to the long axis of the thermostat lever. I thus obtain, with a very compact arrangement of parts, a large movement of the valves 16³ and 17³ for the relatively very 25 small movement of the head of the expansion box 88; and thereby secure a very sensitive regulating action of the thermostatic mechanism.

The operation of this mechanism is in 30 general the same as that of the previously described mechanisms in which the movement of the main gas valve is secured by the balancing and unbalancing of gas pressures on the main gas valve diaphragm. When no 35 water is flowing through the apparatus, the valve 34³ is in its lowest position, the valve 32³ being then closed by the pressure of the spring 90, thus cutting off all flow of water from the chamber 2³ to the chamber 77 and 40 thereby preventing the pressure of water in the main from acting on the rear side of the diaphragm member 9³. At this time the valve 35³ is open allowing the water in the apparatus to pass freely through the port 36³ 45 and circulate through the thermostat chamber 6³ between the inlet 3³ and the outlet 4³ of the heater coils. When a flow of water is started through the apparatus—as by opening an outlet in the hot water discharge pipe 50 7³—the pressure on the upper side of the valve 34³ is immediately reduced and the valve is raised from its seat, thus closing the circulation port 36³ and simultaneously raising the valve 32³ from its seat, thus admitting water from the main to the pipe 76 55 and chamber 77. If at this time the valve 16³ is open—as it will be if the temperature of the flowing water is less than the point of thermostatic cut-off—the water from the 60 main will pass on through the passage-way 78 and exert a pressure on the back of the diaphragm member 9³ sufficient to raise the main gas valve 8³ from its seat against the tension of the spring 79. This will allow 65 fuel to flow from the gas inlet pipe F³ past

the main gas valve to the gas outlet pipe H³ and thence on to the main burners of the heater where it is ignited by the flame of the usual pilot light provided for that purpose. The gas inlet pipe F³ is of course also 70 provided with a main cut-off valve and pilot light connection similar, for example, to that illustrated in Fig. 4, but this main cut-off valve and pilot light connection being ordinarily supplied to all mechanisms of this 75 class, it has not been specifically illustrated in connection with either Fig. 6 or in connection with Figs. 3 and 5. As the temperature of the water flowing through the thermostat chamber rises, the liquid in the thermostat member will expand, forcing down the head of the expansion box 88 and with it the lever 89, thus depressing the right hand end of said lever and raising the left hand end against the tension of the spring 91. 80 This will lift the screw 81 out of engagement with the stem of the valve 16³ and the latter will then be closed by the tension of its own spring 92. The screws 81 and 82 are so adjusted that as the valve 16³ closes, 85 the valve 17³ is simultaneously opened by the engagement of the screw 82 with its stem, and this opening of the valve 17³ allows the water in the shallow space back 90 of the diaphragm 9³ to flow through the pipe 80 and relieve the pressure on the back of said diaphragm member. The main gas valve 8³ will then be closed by the spring 79 thus cutting off the flow of fuel to the 95 main burners of the heater. The temperature of the flowing water will then begin to fall and the liquid in the thermostat member will contract, thus lifting the head of the box 88 out of engagement with the upper end of the bar 89 and allowing the thermostat lever 83 to be moved back to the position shown in the figure by the tension of the spring 91. In this return movement 100 the valve 17³ is closed by the tension of its spring 93 and the valve 16³ simultaneously 105 opened, thus again exposing the back of the diaphragm member 9³ to the pressure of the water in the main. This pressure opens the main gas valve 8³ and admits a fresh 110 supply of fuel to the heating burners. These 115 opening and closing movements of the main gas valve are effected by the successive opening and closing movements of the valves 16³ and 17³ and will continue under the controlling action of the thermostat mechanism as long as water continues to flow through the 120 heater and varies in temperature below and above the predetermined point of thermostatic cut-off, said point being varied as desired by the adjustment of the screws 81 and 82. But as soon as water ceases to flow through the apparatus, the valve 34³ will 125 return to its seat and the valve 32³ will simultaneously be closed by the pressure of the spring 90, thus cutting off communica- 130

tion between the water main and the pipe 76. If at this time the main gas valve 8³ is open, it will remain open until the rise in temperature in the water in the apparatus 5—which can now circulate freely through the thermostat chamber and the port 36³ between the inlet and outlet of the heater coils—rises to the point of thermostatic cut-off, whereupon the valve 17³ will be opened, 10 discharging the water back of the diaphragm 9³ and allowing the main gas valve 8³ to close. As all further supply of water to the pipe 76 and chamber 77 is now cut off, the main gas valve will remain closed until 15 a fresh supply of water is admitted to this pipe and chamber by the opening of the valve 32³ consequent upon a reestablishment of a flow of liquid through the apparatus. 20 Since the pressure of the liquid in the water main is always very much greater than the pressure of gas, the diaphragm member 9³ may be made very small, and the volume of the space back of this diaphragm need not be in most cases more than one- 25 tenth of a cubic inch. The volume of water discharged each time that the main gas valve 8³ is closed is therefore insignificant in comparison with the total volume of water which collects in the drip pan of the 30 heater. Since the number of opening and closing movements of the main gas valve under the action of the thermostatic control is as a matter of fact very small in the ordinary use of heaters of this type, the 35 water escaping through the pipe 80 could be allowed to flow out directly on the cellar floor if it were not for merely sentimental considerations. In some cases where the pressure in the water main is very high, I 40 may place a pressure regulator as indicated at 94—in the pipe 78 so as to prevent an unnecessarily heavy pressure on the back of the actuating diaphragm member 9³. Or in lieu of this I may extend the stud at the center cap 95—which closes the end of the main 45 gas valve casing G³—far enough to the left to allow only a limited movement of the diaphragm member 9³ no matter what may be the pressure of the liquid on the rear side 50 thereof.

In Figs. 7 and 8 I illustrate the construction of other control mechanisms, embodying my invention, in which the main gas valve is actuated in its movement by electro-magnets, the excitation of which is controlled jointly by the position of the water- 55 actuated member and the thermostatically actuated member. The exciting current which serves to energize the electro-magnets and thereby effect the movement of the main gas valve is derived from any suitable source of electric power external to the apparatus itself, or it may, as will presently be explained, be generated by a thermo- 60 electric battery operated by the waste

heat of the escaping flue gases. The parts of the mechanism are so arranged that current is used only while the main gas valve is actually making its opening or closing movements, so that the amount of electric 70 energy used is in all cases very small, and can be readily supplied either by the ordinary bell battery (preferably of the dry cell type) or by a relatively small and comparatively inexpensive thermo-electric battery. 75

Referring first to the construction shown in Fig. 7 (which is drawn to a considerably larger scale than the preceding figures), 1⁴ indicates the cold water pipe leading from the main to the chamber 2⁴ in which the water-actuated valve 34⁴ is located. A pipe 100 extends from the space above this puppet valve to the cold water inlet of the top coil (not shown in this figure). The water 8⁴ after passing through the heater coils emerges as before from the hot water outlet 4⁴, enters the lower end of the thermostat chamber 6⁴, flows upwardly therethrough and out at the top through a pipe (not 90 shown in this figure) leading to the desired point of discharge. The fuel supply enters the main gas valve casing G⁴ through the pipe F⁴ and is led away through the pipe H⁴ which communicates with the main 95 burners of the heater. As in previous cases the main gas inlet pipe F³ is provided with a shut-off cock and a pilot light connection on the inlet side thereof. 8⁴ is the main gas valve which is mounted on a long stem 101 100 that passes through the front cap 102 of the gas valve casing G⁴. This cap is of iron and serves as the yoke of a pair of electric magnets 103 and 104. The outer end of the stem 101 takes a bearing in a second iron 105 plate 105 which serves as the yoke of a pair of electro-magnets 106 and 107. The cores of these four electro-magnets are provided at their inner ends—opposite the yokes 102 and 105—with conical pole pieces, and between these pole pieces is a soft iron armature 106 which is adjustably mounted, as shown, on a long collar 109 secured to the stem 101. The thermostat chamber 6⁴ contains a thermostat of the usual composite 115 construction, similar to that shown in Fig. 4, and this thermostat, since it is not required to directly move the main gas valve, may be of very light construction, and will therefore be very readily influenced by small 120 changes in temperature. The lower knife edge of the inner negative member 55⁴ of this thermostat engages with the upper knife edge groove of an obliquely angled thermostat lever 83⁴ exactly the same in 125 form as that illustrated in Fig. 6 and already fully described in connection therewith. The supporting knife edge of this thermostat lever is mounted on a hard rubber or fiber block 110, and the terminal ad- 130

justing screws 81⁴ and 82⁴ are arranged to engage respectively the spring terminals 111 and 112 that are also mounted on the insulating block 110, and are prevented from rising above the positions shown in the figure by stops 113 and 114 engaging with their outer ends. The thermostat lever 83⁴ is held in operative engagement with the terminal knife edge of the member 55⁴ by means of a compression spring 115, the upper end of which bears upon, and is in electrical engagement with the left hand end of the lever 83⁴, and the lower end of which is supported in a tube 116 of hard rubber or indurated fiber. Mounted loosely on the stem 101 are two collars 117 and 118 of hard rubber or fiber, and on these collars are mounted contact rings 119 and 120; the ring 119 being adapted to close the electrical circuit between the terminal 121 of the magnet 106 and the corresponding adjacent terminal 121' of the magnet 107; while the ring 120 is correspondingly adapted to close the circuit between the terminal 122 of the magnet 103 and the adjacent lower terminal 122' of the magnet 104. Weak springs 123 and 124 are interposed between the collars 117 and 118 and the adjacent opposing faces of the yokes 102 and 105, and serve to keep said collars and the contact rings thereon normally in their circuit closing positions. 125 indicates a battery or other suitable source of current, from one terminal of which a connection 126 is led to the lower end of the spring 115, and through said spring to the insulated thermostat lever 83⁴. The other battery terminal is provided with two connections. One of these, 127, leads directly to one terminal of the magnet 104. The other connection 128 leads to a pivoted arm 129 which is weighted at its outer end and is connected at that point to a thin wire stem 33⁴ that passes upward through a stuffing box in the lower side of the chamber 2⁴ and is secured at its upper end to the puppet valve member 34⁴. The arm 129 is mounted on an insulating block secured to the hard rubber head of the magnet 107, and carries a terminal 130 which, when the arm 129 is raised, makes contact with the lower terminal of the magnet 107. The upper terminals of the magnets 103 and 106 are connected respectively to the spring contact arms 112 and 111.

55 In describing the operation of the control mechanism of Fig. 7, I will assume that the parts are in the position shown in the figure in which the main gas valve 8⁴ is closed and the temperature of the water in the thermostat chamber is below the point at which the thermostatic mechanism acts to close the main gas valve. As long as no water flows through the heater no movement of the thermostat lever—accidental or otherwise—can bring about any change

in the position of the electro-magnetically operated parts of the mechanism, nor close the circuit through the magnets; because under the above conditions the circuit through the magnet coils 106 and 107 is interrupted at the terminal point 130, while the circuit through the magnets 103 and 104 is broken at the contact ring 120. But as soon as a flow of water is started through the apparatus by opening some tap or bib in the discharge pipe for the house supply, the pressure on the top of the puppet valve 34⁴ is reduced and this valve is raised by the water flowing in through the pipe 1⁴. The raising of this valve lifts the lever 129 and brings the terminal 130 into engagement with the lower contact block of the magnet 107. Current now flows from the battery 125 through the connection 123, the spring 115, the contact screw 81⁴, the spring terminal 111, the magnet coil 106, the contact ring 119, the magnet coil 107, the lever 129, and the return battery connection 128. This energizes the left hand pair of electric magnets and draws the armature 108 in the corresponding direction, thus opening the main gas valve 8⁴ and allowing a supply of fuel to pass through the gas outlet pipe 1 to the main burners of the heater where it is ignited by the flame of the pilot light provided for that purpose. As the armature 108 is moved to the left—carrying with it the sleeve 109—the left hand end of said sleeve strikes the collar 117 and moves the contact ring 119 out of engagement with the adjacent terminal of the magnets 106 and 107 and breaks the electric circuit through the coils of said magnets just before the armature 108 reaches its extreme left hand limit of movement. 105 This movement is determined by the engagement of the coned leather washer 61⁴—similar to the corresponding washer used in the construction of Fig. 4—with the correspondingly coned recess about the stem 110 opening in the cap or yoke 102; and this engagement also serves to seal the opening around the stem 101 against any leakage of gas and eliminate the necessity for using a stuffing box for preventing such leakage. 110 The parts of the control mechanism will remain in the position just described—with the main gas valve open—until the temperature of the water in the thermostat chamber 6⁴ has risen to the point of thermostatic cut-off, which can be varied by the adjustment of the screws 81⁴ and 82⁴. At this point the expansion of the thermostat member has withdrawn the terminal knife edge of the element 55⁴ sufficiently to allow the 125 spring 115—acting on the left hand end of the thermostat lever 83⁴—to bring the right hand terminal screw 82⁴ into contact with the spring clip 112 and lift the screw 81⁴ out of contact with the spring clip 111. The 130

circuit now flows from the battery 125 through the connection 126, the spring 115, the thermostat lever 83⁴, the terminal screw 82⁴, the spring arm 112, the coil of the magnet 103, the contact ring 120, (this contact ring having now been brought in engagement with the adjacent magnet terminals by the left hand movement of the sleeve 109) the coil of the magnet 104, and the return battery connection 127. This energizes the right hand set of electromagnets and pulls the armature 108 to the right, thus closing the main gas valve 8⁴ and shutting off the flow of fuel to the main heating burners. Just before the armature 108 reaches the limit of its right hand movement, the end of the sleeve 109 engages with the collar 118 and carries it, and the contact ring 120 thereon, out of engagement with the adjacent contact terminals of the magnets 103 and 104, thus breaking the circuit through said magnets. Both the support of the washer 61⁴ and the main gas valve 8⁴ are so adjusted on the stem 101 that the movements of the armature 108 to the left and to the right are arrested before said armature can come in contact with the poles of the left and right hand sets of magnets; and to further guard against such contact, brass stops may—if desired—be inserted in the heads of the magnet coils. When closed, the gas valve is held against its seat both by the friction of the stem 101 in its bearings, and also by the residual magnetism in the cores of the right hand set of electro-magnets 103 and 104, and if necessary, a weak compression spring 131—whose tension is just sufficient to balance the gas pressure on the right hand side 40 of the valve 8⁴—may be interposed between the cap 102 and the main gas valve head. If the flow of water continues until the temperature of the liquid in the thermostat chamber has been reduced below the 45 point of thermostatic cut-off, the contraction of the thermostat element will depress the left hand end of the thermostat lever 83⁴, and bring the terminal 81⁴ once more in engagement with the contact spring 111. This allows the current from the battery 125 to again flow through the magnets 106 and 107, as already described and the resultant excitation of these magnets moves the armature 108 to the left again opening the 55 gas valve 8⁴ and admitting a fresh supply of fuel to the main burners. These successive opening and closing movements of the valve 8⁴ will continue as long as water continues to flow through the thermostat chamber and to successively fall below and rise above the temperature at which the thermostat mechanism is adjusted to close the contacts at 81⁴ and 82⁴. But when the flow of water is shut off, the pressures on the two 65 sides of the puppet valve 34⁴ are at once

equalized, the latter will drop to its seat, and the weighted lever 129 will also fall, breaking the circuit at the terminal point 130, and preventing any further flow of current through the left hand set of magnet coils. If, at the time the water is shut off, the gas valve is closed, it will remain closed until the flow of water is once more started through the heater. If the gas valve is open when the flow of water is stopped, it will remain open only long enough to allow the water in the thermostat chamber to be raised to the point of thermostatic cut-off, and will then be shut by the closing of the contact at 82⁴ and the resultant excitation of the right hand set of magnets 103 and 104. This will bring the parts into the position shown in the figure, in which position, as already explained, no further current can flow through either set of magnet coils, until the terminal 130 has once more been closed by the lifting of the valve 34⁴.

The construction illustrated in Fig. 8 is of the same general character as that illustrated in Fig. 7, but differs from the latter in some mechanical details. In this apparatus only a single set of magnet coils is used to produce the double opening and closing movements of the gas valve. Only one of the coils 132 of this set is shown, this coil being located just behind the sectional plane of illustration which is taken through the center of the apparatus. The other coil is symmetrically located just in front of this central sectional plane, the cores of the two coils being joined by the yoke 133. The gas valve 8⁶ is pivotally mounted in the forked end of a lever 134 that is mounted on an axis 134^a and carries at its lower end an armature 135 which swings in close proximity to the poles of the connected electro-magnets. One fork of the arms of the lever 134 is extended upward at one side of the valve 8⁶ to carry a contact brush 136 that engages with the insulated commutator segments 137 and 138. In this construction the water from the main passes directly into the cold water inlet of the heater (not shown in the drawing) and after flowing through the heater coils, emerges from the outlet 4⁶, enters the side of the thermostat chamber 6⁴, and after passing therethrough, flows out into a chamber 139 in which I place the water actuated puppet valve member 140. The thermostat which I use in this construction is of the liquid type, and consists of a corrugated box 141 which is hermetically closed at both ends and is filled with a suitable expansion medium. I prefer to employ for this purpose some relatively dense and more or less viscous liquid like petroleum oil or olive oil or some material like paraffin or an eutectic alloy such as Wood's metal, which is solid at low temperatures, but which becomes liquid at temperatures less than that for which

the thermostat is designed to actuate the cut-off mechanism.

The lower head of the thermostat member 141 is recessed to engage the upper end of a short stem 142 which passes down through a stuffing box in the bottom head of the thermostat chamber 6⁵, and engages at its lower end with the short arm of a bell crank thermostat lever 143. The long arm of this lever is provided with a contact pin 144 mounted on an insulating block 145. Adjacent to the two ends of the contact pin 144 I arrange two contact terminals 146 and 147, both mounted on an insulating block of hard rubber or fiber secured to the right hand wall of the gas valve casing G⁵. The puppet valve 140 which is arranged in the outlet passage from the thermostat chamber, is provided with a stem 33⁵ which passes downward through a stuffing box in the lower wall of the chamber 139, and bears at its lower end on a spring contact arm 148. The valve 140 is normally held in the position shown in the figure—in which the contact arm 148 is moved away from the contact block 149—by a compression spring 150. From one pole of the battery 125⁵ a connection 151 is led to a terminal of the set of electro-magnetic coils, and from the other terminal of said coils—which are arranged in series with each other—a second connection 152 is led through the lever 134 to the insulated brush 136. The two commutator segments 138 and 137 are connected respectively to the terminal 147 and the contact arm 148; and from the contact block 149, another connection 153 leads to the terminal 146. The other pole of the battery is connected by a wire 154 to the contact pin 144 in the end of the thermostat lever 143. The latter is normally held in the position shown in the figure—in which the contact 144 is in engagement with the terminal 146—by means of a compression spring 155 engaging with the lateral projection on the lever 143.

The operation of this mechanism is in general the same as that of Fig. 7. It will therefore be readily understood with a very brief description. When no water is flowing through the apparatus, the valve 140 will be held closed by the spring 150 and the contact arm 142 will be out of engagement with the terminal 149. If the temperature of the water in the thermostat chamber 6⁵ is at such time below the point of predetermined cut-off (as it will always be after the completion of the last cycle of control operations) the thermostat member will be out of engagement with the stem 142 and the lever 143 will be held in position shown in the figure by the spring 155. In this position of the parts no current can pass through the magnet coils until a flow of water has been started through the apparatus by opening some point of outlet in

the discharge pipe 7⁵. When this is done, the valve 140 will be lifted from its seat to allow the water to flow from the heater to the point of outlet, and this lifting of the valve and its connected stem 33⁵ will allow 70 the terminal of the spring contact arm 148 to come into engagement with the block 149. This will close the circuit through the magnet coils, the current now flowing from one pole of the battery 125⁵ to the contact 75 145 thence through the connection 153 and contact 149 to the contact arm 148, thence to the commutator segment 137 and brush 136 bearing thereon, thence through the connection 152 to the magnet coils in series 80 and from the latter to the battery through the return wire 151. The resultant excitation of the electro-magnets attracts the armature 135 and swings the arm 134 to the right, thus lifting the main gas valve 8⁵ 85 away from its seat. As this arm passes the vertical, the circuit through the magnet coils is broken by the passage of the brush 136 from the commutator segment 137, but the arm continues to swing to the left under 90 the inertia of its initial movement until it assumes the position indicated by the dotted lines in the figure. The opening of the gas valve allows fuel to flow from the gas inlet pipe F⁵ to the gas outlet pipe H⁵ and 95 thence on to the main burners of the heater where it is of course ignited by the usual pilot light. The heat of the main burners immediately begins to raise the temperature of the flowing water, and this in turn expands the material in the thermostat box 141 and depresses the stem 142 thereby moving the thermostat lever 143 to the right 100 against the pressure of the spring 155, and ultimately bringing the contact 144 into engagement with the adjustable terminal 147. When this occurs, the circuit is again 105 closed through the magnet coils by the passage of the current from the contact 144 to the terminal 147, thence to the commutator segment 138 and brush 136 now bearing 110 on that segment, thence through the connection 152 and the two magnet coils in series, back again to the other battery terminal. The magnetic field thus created again 115 attracts the armature 135 toward the poles of the magnet system, and this moves the arm 134 from the dotted position back to the full line position. As this arm passes the vertical, the current is once more broken 120 through the magnet coils by the brush 136 leaving the commutator 138, but as before the arm continues its motion until the main gas valve 8⁵ has reached its seat and cut off the flow of fuel through the gas valve 125 chamber. The weight of the gas valve is sufficient to hold the latter firmly against its seat against the slight pressure of the gas in the inlet pipe, and the valve will remain closed until the temperature of the 130

flowing water has fallen sufficiently to withdraw the stem 142 from engagement with the thermostat lever 143 and allow the latter to be once more brought to the position shown in the figure by the tension of the spring 155. The circuit will then be once more closed through the magnet coils in the manner already described and the gas valve opened again. As long as water continues to flow, these opening and closing movements will occur in regular succession as the circuit through the magnet coil is established by successive contacts of the pin 144 with the terminals 146 and 147; the temperatures at which these movements occur being varied at will by the joint adjustment of the contact screw 147 and the screw 156, which latter screw varies the position of the lower head of the thermostat member by varying the volume of space within the thermostat box. But when water ceases to flow, the valve 140 is returned to its seat by the pressure of the spring 150, and the resultant downward movement of the stem 35 moves the terminal of the arm 148 out of engagement with the block 149 thereby preventing any further flow of current through the magnet coils when the main gas valve is in its closed position. If the flow of water is shut off while the main gas valve is open, it will remain open only long enough to allow the temperature of the water in the heater or the thermostat chamber to be raised to the point of predetermined cut-off. When this point is reached, the main gas valve will be closed, in the manner already described, and will remain closed from that time on until the flow of water has been re-established and the valve member 140 again raised.

In Fig. 8 I illustrate a means for recharging the battery 125⁶ each time that the apparatus is put into service. The means there shown comprises a thermo-electric battery 157 which is placed at any convenient place in the chimney or flue leading from the heating chamber and is provided with connections 158 and 159 which lead from the terminals of said battery to the terminals of the battery 125⁶. When the one set of terminals of the battery 157 is exposed to the hot gases escaping from the heating chamber, current is generated which re-charges the battery 125⁶, the construction of the battery 157 being of course such that the voltage of the thermo-electric current thus produced, is on the average slightly in excess of the voltage of the battery 125⁶. In order to avoid any flow of current from the battery 125⁶ through the charging battery 157, when the heat is shut off, one of the connections, as 158, is led through a switch contact 160 which is closed only when the water is flowing, and when consequently

hot gases are escaping from the heating chamber. Other automatic means controlled by the operation of either the water-actuated member or the thermostatically-actuated member, may of course be employed for the recharging of the battery 125⁶ each time that the heating apparatus is put in service.

It will be readily apparent to any one skilled in the art that the various mechanisms previously described may be equally well used for the control of the fuel supply to the burners of a storage tank heater. It will also now be readily apparent that various detail modifications of these mechanisms—involving nothing more than the exercise of ordinary mechanical skill—may be readily made to adapt them for use on other specific forms of heating apparatus than those herein shown and described.

Having thus described my invention and illustrated its use, what I claim as new and desire to secure by Letters Patent is the following:

1. In an automatic water heater, a burner, a gas valve for controlling the supply of gas to the burner, a member actuated by the differences of water pressure caused by opening and closing the outlet from the heater, a thermostatic means operated by the heater water, means actuated by fluid pressure for operating the gas valve, and two valves for controlling the application of the fluid pressure to the power controlled means arranged in series in the line of flow of such fluid pressure, one of such valves being operated by the water-actuated member and the other of such valves being operated by the thermostatic means.

2. In an automatic water heater, a burner, a gas valve for controlling the supply of gas to the burner, a member actuated by the differences of water pressure caused by opening and closing the outlet from the heater, a thermostatic means operated by the heater water, means actuated by fluid pressure for operating the gas valve, and two valves for controlling the application of the fluid pressure to the power controlled means arranged in series in the line of flow of such fluid pressure, one of such valves being operated by the water-actuated member and the other of such valves being operated by the thermostatic means, and the first of said two valves being arranged to cut off the application of the fluid pressure when the outlet from the heater is closed, and the second of such valves being arranged to permit the application of the fluid pressure when the heater water is below a predetermined temperature for which the thermostatic means is set, and the first valve is open.

3. In an automatic water heater, a burner, a gas valve for controlling the supply of gas to the burner, a member actuated by the differences of water pressure caused by

opening and closing the outlet from the heater, a thermostatic means operated by the heater water, means actuated by fluid pressure for operating the gas valve, and two valves for controlling the application of the fluid pressure to the power controlled means arranged in series in the line of flow of such fluid pressure, one of such valves being moved to open position through the movement of the water-actuated member when the outlet from the heater is opened, and the other of such valves being held in open position when the heater water is below a predetermined temperature and moved to closed position by the thermostatic means when the heater water reaches a temperature above such predetermined temperature.

4. In an automatic water heater, a burner, a gas valve for controlling the supply of gas to the burner, a member actuated by the differences of water pressure caused by opening and closing the outlet from the heater, a thermostatic means operated by the heater water, an abutment actuated by fluid pressure for operating the gas valve, two valves for controlling the application of fluid pressure to the said abutment arranged in series in the line of flow of such fluid pressure, one of such valves being operated by the water-

actuated member and the other of such valves being operated by the thermostatic means, and a third valve also operated by the thermostatic means to permit an exhaust of fluid pressure from behind the said abutment when the first thermostatically operated valve is closed.

5. In an automatic water heater, a burner, a gas valve for controlling the supply of gas to the burner, a member actuated by the differences of water pressure caused by opening and closing the outlet from the heater, a thermostatic means operated by the heater water, power controlled means for opening the gas valve and for closing it, a source of power for supplying power to positively move the said means in both directions, and two means for controlling the application of power to the power-controlled means, one of such means being operated by the water-actuated member and the other of such means being operated by the thermostatic means.

In testimony whereof I have hereunto signed my name in the presence of the two subscribed witnesses.

FRANK L. O. WADSWORTH.
